SPRINKLER

John Erickson and Olof M. Lilliequist, Spokane,
Wash.

Application December 1, 1933, Serial No. 700,490

1 Claim. (Cl. 299—18)

Our invention relates to improvements in lawn sprinklers and the main object is to provide a novel and simple form of sprinkler head readily attachable to a garden hose or automatic 5 sprinkler and which will throw a square spray or sheet of water covering a square area of ground surrounding the sprinkler.

Another object is to provide a sprinkler which may be readily adjusted to vary the density of the 10 spray and the distance to which it is thrown.

A further object is to provide a spray head including a body portion for receiving the water and which terminates in a depressed bowl shaped water guide at one end in which a spray nozzle 15 is seated having apertures to release the water and on which an adjusting cap is threaded to vary the area of the apertures exposed.

With these and other objects in view the invention resides in the novel construction and arrangement of parts as hereinafter set forth and claimed, reference being had to the accompanying drawing wherein:

Figure 1 is a side view of our sprinkler.

Figure 2 is an end view.

Figure 3 is a plan view.

Figure 4 is an enlarged section along the line 4—4 in Figure 2.

Figure 5 is a detail cross section along the line 5—5 in Figure 4.

Figure 6 is a detached side elevation of the spray nozzle alone.

Figure 7 is a side elevation of a modified form of sprinkler suitable for attachment to a conventional automatic sprinkler.

Referring now with more particularity to the drawing our invention comprises a body portion or head 1 having a projecting flat mounting foot or flange 2 pierced with screw holes 3 by which it may be anchored to any supporting surface.

40 In one end the body 1 has a tapped socket 4 adapted to receive the end of the hose A which bears against a rubber gasket or washer 5 to provide a water tight joint at this point. The socket 4 communicates at its inner end with a passage 45 or bore 6 of smaller diameter extended into the body 1 for some distance and then turned upwardly and emerging from the top thereof centrally through a boss 7 formed on the top and inner end of said body. This boss has a cup or 50 bowl shaped depression 8 concentric with the opening of the bore 6 and the upstanding walls or margins 9 thus formed are rounded off in four equal lips, wings or tongues as indicated at 10.

The upper mouth of the bore 6 is tapped as at 11 55 for some distance down into the bore to receive

a tubular spray nozzle or sleeve 12 complementarily threaded adjacent its lower end at 13. Just above these threads 13 said nozzle has four diametrically opposed and equally spaced spray openings 14 and when the nozzle is screwed down into the bore 6 it may be adjusted so that any desired area of these openings will be exposed above the depression 8 as will be understood in Figure 4, the openings being finally located in alignment with the centers of the lips 10 as shown. Screw driver kerfs 15 are provided in the top of the nozzle to facilitate its adjustment.

The nozzle 12 is also threaded at its upper end at 16 above the openings 14 whereby to receive a spray regulating cap 17 tapped within its tubular wall 18 and having a closed end 19 with screw driver kerf 20 and small vent apertures 21. The threads 16 are preferably of extended or projecting form and the cap 17 is of such length that it may be turned down over the nozzle 12 far enough that the lower margin of its wall 18 will project over and obstruct any desired part of the openings 14 also as shown in Figure 4.

From the foregoing it will be apparent that 25 water entering the bore 6 under pressure will emerge from the nozzle openings 14 in the form of four fan shaped sprays deflected upwardly and outwardly by the rounded lips 10 and finally falling to the ground along the four sides of the square defined as with the spray nozzle as its center. By varying the adjustment of the cap 17 more or less of the openings 14 may be opened whereby to vary the density of the spray and the area covered thereby as will be understood. A fine vertical 30 spray will also emerge from each of the vents 21 in the cap to cover the ground immediately around the spray nozzle. The lower margin of the cap 17 is preferably beveled off as indicated at 22 so as not to deflect the spray emerging from the openings 14.

In Figure 7 a modification of our invention is shown particularly adapted for mounting on existing conventional forms of automatic sprinklers, this modification including a straight tubular body portion 1a having a socket 4a to fit on the base (not shown) of the sprinkler and having the assembly of lips 10a, cap 17a, passage 6a and spray nozzle (not shown) at its upper end exactly as hereinbefore fully set forth. The operation and adjustment is of course the same. The body portion has wrench flats 23 to facilitate its mounting on the sprinkler and the body may vary in length, diameter and size of socket 4a to fit any desired supporting element or sprinkler.

While we have herein set forth a certain pre-

ferred manner and manner of assembling the elements of our invention it is understood that we may vary from the same in minor structural details so as best to provide a practical device for the purposes intended, not departing from the spirit of the invention and within the scope of the appended claim.

We claim:

- 10 In a device of the kind described, a body portion for positioning upon the ground, the body having an angular water-way therethru with one mouth thereof directed upwardly when the body portion is operatively positioned on the ground, this mouth being surrounded by a bowl shaped depression the up-standing outer margins thereof being divided into four co-equal arcuate lips, the inner wall of the said mouth being tapped,
- 15

5 a tubular spray nozzle threaded exteriorly at each end and threadedly engaging at one end the said upper mouth of the water way of the body portion, the nozzle being pierced by four spray openings equi-spaced therearound in approximate alignment with the bottom of the bowl shaped depression, and a tubular spray regulating cap closed at its predetermined outer end and interiorly threaded at the opposite end and thereby threadedly mounted over the upper end of the 10 nozzle, the cap being so dimensioned that it may be turned down over the said spray openings of the nozzle for regulating the flow of water therethrough, and means for receiving a tool for adjusting both the said nozzle and the regulating cap. 15

JOHN ERICKSON.

OLOF M. LILLIEQUIST.
